Certificate of Correction.

It is hereby certified that Design Letters Patent No. 62,975, granted September 4, 1923, upon the application of Charles W. Bailey, of Philadelphia, Pennsylvania, for a "Design for a Ring," were erroneously issued to the inventor, said Bailey, whereas said Letters Patent should have been issued to Bailey, Banks & Biddle Co., Philadelphia, Pennsylvania, a Corporation of Pennsylvania, as shown by the records of assignments in this office; and that the said Letters Patent should be read with this correction therein that the same may conform to the record of the case in the Patent Office.

Signed and sealed this 16th day of October, A. D., 1923.

UNITED STATES PATENT OFFICE.

CHARLES W. BAILEY, OF PHILADELPHIA, PENNSYLVANIA.

DESIGN FOR A RING.

Application filed August 16, 1922. Serial No. 3,400. Term of patent 7 years.

To all whom it may concern:

Be it known that I, CHARLES W. BAILEY, a citizen of the United States, residing in the city and county of Philadelphia, State of Pennsylvania, have invented a new, original, and ornamental Design for Rings, of which the following is a specification, reference being had to the accompanying drawing, forming a part thereof.

The figure is a side elevation of a ring showing my new design.

I claim:

The ornamental design for a ring as shown.

CHARLES W. BAILEY.
